EQUALIZING DEVICE

Samuel J. Moran, Los Angeles, Calif., assignor
to Sumner C. Bryant, trustee, Los Angeles, Calif.

Application August 27, 1940, Serial No. 354,348

7 Claims. (Cl. 187—1)

This invention relates to devices for equalizing the strain in a plurality of tension members. It is of particular utility for use in connection with elevators and elevator cables and, for the purpose of illustration, will be described in connection therewith, although I do not intend to be limited to such use as the device is susceptible of use in many different fields of industry.

This invention is an improvement on the construction shown in my Patent No. 1,912,537, issued June 6, 1933, to which reference is hereby made.

It is well known that when a unitary tensile force is applied to an object through a plurality of members, such as cables, one of these members may have a tendency to stretch and that such stretching action throws nearly all of the load upon the other members. It is the primary object of this invention to produce a device which may be employed in attaching members of the class referred to above to the object, such device being constructed so as to effect an automatic adjustment in the length of the members which will bring about an equalization of forces among the various members.

It is well known to those familiar with the elevator art that the usual construction employed in elevators consists of a cage which is suspended in the elevator shaft by a plurality of cables, such cables running over a power drum in the top of the shaft and extending downwardly through the shaft to form loops having their lower end portions attached to the bottom of the cage. Counterweights are of course attached to the cables at their intermediate portions. In structures of this nature it has been found that after a comparatively brief period of use one or more of the cables has a tendency to stretch. This throws practically the entire load of the cage upon the other cables, and to compensate for this stretching action the cables are usually attached to the top of the cage through the medium of turn-buckles or other similar adjustable connection.

It has been found practically impossible to maintain uniform tension in the cables through the use of manual adjustments of the type referred to above. Numerous attempts have been made to perfect an attaching member for use in connecting cables of this nature to the elevator cage which will automatically maintain an equal strain in all of the tension members.

It is a further object of this invention to produce an equalizing device of the class described which contains a non-fluid equalizing medium.

The general construction of the device contemplated by this invention consists of a housing provided with a chamber containing a plurality of plunger members. Each of the plunger members is attached to one of the tension members, and the chamber is filled with a yieldable non-fluid medium, which in the preferred form of my invention consists of a body of metal spheres or ball bearings. It is in the manner in which such ball bearings are positioned relative to the plunger members in which my present invention is an improvement over that disclosed in my said Patent No. 1,912,537.

Other objects and advantages will be apparent from the following specification and the drawing, which is for the purpose of illustration only, and in which:

Fig. 1 is a side view, partly in section, showing one side of my invention connected to a plurality of cables;

Fig. 2 is a cross-sectional view taken on the line X—X of Fig. 1.

Referring to the drawing, Fig. 1 shows a retaining means 10, adapted to be suitably secured to an elevator cage (not shown) or other device to be lifted, as described in my said Patent No. 1,912,537. Slidably received in the retaining means 10 are plunger means 11 comprising a first set of plungers 12, 13, and 14, and a second set of plungers 12a, 13a, and 14a, as best shown in Fig. 2. Since the two sets of plungers operate in the same manner, only the first set comprising the plungers 12, 13, and 14 will be described herein. Adapted to separate the plunger means 11 from the retaining means 10, and to maintain a rigid connection therebetween, is a bearing means 15 comprised of a continuous chain of separate ball bearings 16.

Since the plungers 12, 13, and 14 are all similarly secured relative to the retaining means 10, the manner in which the plunger 12 is secured will be described in detail, omitting the specific detailed construction of the retaining means for the other plungers.

The retaining means 10 is comprised of a central vertically disposed member 17 to which is secured a first end member 18 by means of bolts 19 and 20, the bolts 20 also securing relative to the first end member 18 and the central member 17 a first track means 21 comprising a lower portion 22 and an upper separate portion 23. The lower portion 22 of the first track means 21 is provided with a centrally disposed longitudinal groove 24 which terminates just below the upper end of the lower portion 22 in a shoul-

der 25. Also formed in the lower portion 22 of the first track means 21 is a cup-shaped longitudinal bearing groove 27 axially aligned with the longitudinal groove 24 and in which the ball bearings 16 are adapted to be received. As will be noted, the upper end of the lower portion 22 of the first track means 21 is rounded, as at 28, and the bearing groove 27 continues around the periphery thereof. The upper portion 23 of the first track means 21 is provided with a semi-circular opening 29 mating with the rounded end 28 of the lower portion 22, and having therein a bearing groove 30 mating with the bearing groove 27, to form a top bearing passage 31 adapted to receive the ball bearings 16.

The plunger 12 is comprised of an upper member 34 and a lower member 35 adapted to be held rigid relative to each other by longitudinal straps 36 and 37 secured together at their lower ends by rivets 38 passing through the straps and the lower member 35, and secured together at their upper ends by a rivet 39. The lower end of the upper member 34 is rounded to form a semi-circular end 40 which mates with the concavely rounded upper end of the lower member 35. A cup-shaped groove 41 is provided entirely around the edge of the upper member 34 and cooperates with the bearing groove 27 of the first track means 21 to retain the ball bearings 16 therebetween. The lower member 35 is provided with a concave upper end mating with the lower rounded end 40 of the upper member 34, and has formed therein a cup-shaped groove 43 complementary to the groove 41 in the upper member to confine the ball bearings 16 therebetween, the lower member 35 being provided with inner and outer plates 44 and 45 respectively, held in place by the longitudinal straps 36 and 37. Also formed on the lower member 35 is a tongue 46 slidably engaging in the longitudinal groove 24 of the first track means 21 and limited in its upward motion therein by the shoulder 25. Also formed in the upper member 34 of the plunger 12 is a longitudinal groove 47 having a shoulder 48 at its lower end, the groove being adapted to receive a tongue 49 formed on the upper portion 23 of the first track means 21, engagement of the shoulder 48 with the lower end of the tongue 49 operating as a stop to limit upward movement of the plunger 12.

Second track means 50 are also secured to the central member 17 by means of bolts 51, and comprise an upper portion 52 and a lower portion 53. The lower portion has an upper rounded end 54 and has provided in its sides and upper end a cup-shaped groove 55 adapted to assist in confining the ball bearings 16. Similarly, the upper portion 52 of the second track means 50 is provided with a concave lower end having a cup-shaped groove 56 therein cooperating with the groove 55. The lower portion 53 of the second track means 50 also has a longitudinal groove 57 therein adapted to receive a second tongue 58 formed on the lower member 35 of the plunger 12, and has a shoulder 59 at its upper end acting as an upper stop to limit upward movement of the plunger 12.

A third track means 62 is fixed to the central member 17 similarly to the second track means 50 and is in all respects identical therewith, cooperating with the plungers 13 and 14 in the same manner that the second track means 50 cooperates with the plungers 12 and 13.

A fourth track means 63 is likewise fixed to

the central member 17 similarly to the first track means 21, and is similar in construction thereto. The fourth track means 63 cooperates with the plunger 14 and closes the end of the retaining means 10.

As will be noted, the ball bearings 16 are retained in the cup-shaped grooves formed in the track means and plungers, and form a continuous chain of ball bearings therein, each ball bearing of which is separate from the others, although they are in linear engagement. It is also to be noted that the ball bearings 16 are free to flow or move in the cup-shaped grooves provided therefor.

15 The plunger 12 is provided with an eye member 65 pivoted to the rivet 39 and being connected to a suitable cable 66 from which the plunger 12 is suspended. Similarly, the plungers 13 and 14 are connected to suspending cables 20 67 and 68 respectively.

In operation, the bearing means 15, through the ball bearings 16, equalizes the tension in the cables 66, 67, and 68. If one of the cables, such as the cable 66, stretches so as to normally reduce the tension thereon, the increase in tension caused thereby on the cables 67 and 68 as a result of the increase in weight on such cables causes this increase in tension to be communicated to the plunger 12 through the ball bearings 16 from the plungers 13 and 14, thus equalizing the tension on all of the plungers. Thus, it will be understood that any stretching of the cables 66, 67, or 68, due to normal wear and use, and the variation in tension which would normally be caused therebetween due to such stretching, will be equalized between the cables immediately by the ball bearing construction shown and described. As will be understood, the second set of plungers 12a, 13a, and 14a is designed to be attached to a second set of cables, so as to provide a construction as shown for equalizing the tension between six supporting cables. It will be understood, however, that any desired number of cables and plungers may be used without departing from the spirit of the invention, since the invention will operate with two or more cable and plunger constructions.

Although I have illustrated and described my invention in a preferred form, it will be understood that certain parts, elements, and units thereof may be replaced by other parts, elements, and units having the same mode of operation without departing from the spirit of my invention, and therefore I do not intend to be limited by the embodiment described but wish to be afforded the full scope of the following claims.

I claim as my invention:

1. In a device of the character described, the combination of: retaining means having a continuous channel therein; a plurality of plungers slidably retained in said retaining means each adapted to be connected to a tension member, each of said plungers having a groove therearound cooperating with a portion of said channel; and a plurality of ball bearings movably disposed in said channel in contiguous relation and engaging said grooves so as to receive the thrust from all of said plungers and equalize the tensions in said tension members.

2. In a device of the character described, the combination of: retaining means; a first plunger slidably disposed in said retaining means; a second plunger slidably disposed in said retaining means; a first tension member attached to said

first plunger; a second tension member attached to said second plunger; and a single line of ball bearings in contiguous relation disposed in said retaining means between said retaining means and said plungers and adapted to receive the thrust of said plungers, said ball bearings being movable in response to differences in thrust thereon by said plungers to equalize the tensions in said tension members.

3. In a device of the character described, the combination of: retaining means; a first plunger slidably disposed in said retaining means; first stop means for limiting movement of said first plunger in said retaining means; a second plunger slidably disposed in said retaining means; second stop means for limiting movement of said second plunger in said retaining means; a first tension member attached to said first plunger; a second tension member attached to said second plunger; and a single line of ball bearings in contiguous relation disposed in said retaining means between said retaining means and said plungers and adapted to receive the thrust of said plungers, said ball bearings being movable in response to differences in thrust thereon by said plungers to equalize the tensions in said tension members.

4. In a device of the character described, the combination of: retaining means; a first plunger slidably disposed in said retaining means; a second plunger slidably disposed in said retaining means; a first tension member attached to said first plunger; a second tension member attached to said second plunger; walls forming a ball passage in said retaining means; walls forming a ball passage in each of said plungers, said passages in said plungers and said passage in said retaining means forming a continuous passage; and ball bearings in said continuous passage in contiguous relation and adapted to receive the thrust of said plungers, said ball bearings being movable in response to differences in thrust thereon by said plungers to equalize the tensions in said tension members.

5. In a device of the character described, the combination of: retaining means; a first plunger slidably disposed in said retaining means; a second plunger slidably disposed in said retaining means; a first tension member attached to said first plunger; a second tension member attached to said second plunger; walls forming a ball passage in said retaining means; walls forming a ball passage in each of said plungers, said passages in said plungers and said passage in said retaining means forming a continuous passage; ball bearings in said continuous passage in contiguous relation and adapted to receive the thrust

of said plungers, said ball bearings being movable in response to differences in thrust thereon by said plungers to equalize the tensions in said tension members; and stop means for limiting 5 the movement of both said plungers relative to said retaining means.

6. In a device of the character described, the combination of: retaining means including a central member and first, second, and third track means secured thereto, said track means having formed therein a ball bearing passage; a first plunger slidably disposed between said first and second track means, said first plunger having a first bearing passage therein adapted to form a continuous part of said ball bearing passage; a second plunger slidably disposed between said second and third track means, said second plunger having a second bearing passage therein adapted to form a continuous part of said ball bearing passage, said first and second bearing passages and said ball bearing passage forming a continuous passage; a first tension member attached to said first plunger; a second tension member attached to said second plunger; and ball bearings in said continuous passage in contiguous relation and adapted to receive the thrust of said plungers, said ball bearings being movable in response to differences in thrust thereon by said plungers to equalize the tensions in said tension members.

7. In a device of the character described, the combination of: retaining means including a central member and first, second, and third track means secured thereto, said track means having formed therein a ball bearing passage; a first plunger slidably disposed between said first and second track means, said first plunger having a first bearing passage therein adapted to form a continuous part of said ball bearing passage; a second plunger slidably disposed between said second and third track means, said second plunger having a second bearing passage therein adapted to form a continuous part of said ball bearing passage, said first and second bearing passages and said ball bearing passage forming a continuous passage; a first tension member attached to said first plunger; a second tension member attached to said second plunger; ball bearings in said continuous passage in contiguous relation and adapted to receive the thrust of said plungers, said ball bearings being movable in response to differences in thrust thereon by said plungers to equalize the tensions in said tension members; and stop means for limiting 55 the movement of both said plungers relative to said retaining means.

SAMUEL J. MORAN.
